UNITED STATES PATENT OFFICE.

WILLIAM S. TURNER, OF GREENSBURG, PENNSYLVANIA.

HEATER.

No. 867,768.

Specification of Letters Patent.

Patented Oct. 8, 1907.

Application filed June 13, 1907. Serial No. 378,852.

To all whom it may concern:

Be it known that I, WILLIAM S. TURNER, a citizen of the United States of America, residing at Greensburg, in the county of Westmoreland and State of Pennsylvania, 5 have invented certain new and useful Improvements in Heaters, of which the following is a specification, reference being had therein to the accompanying drawing.

This invention relates to improvements in heaters, and more particularly to that type of heater wherein 10 gas is employed as a heat generating medium.

The invention has for its object to provide a heater wherein novel means is employed for heating a large supply of cold air admitted to the heater.

My invention aims to provide a heater having a high 15 degree of efficiency obtained by a minimum expenditure of fuel. To this end, I have devised a heater, or as it may be termed, a furnace, particularly designed for heating halls and compartments, the heater or furnace being suitably supported in the basement of a building, 20 whereby cold air will have free access to the bottom of the heater. The top of the heater can be connected direct to a register in the floor of a building or by conduits or flues to the compartments of the building.

The detailed construction entering into my invention 25 will be presently described and then specifically pointed out in the appended claims.

In the drawing, Figure 1 is a vertical sectional view of a portion of the heater. Fig. 2 is a vertical transverse sectional view of the same. Fig. 3 is a bottom plan of 30 the heater, and Fig. 4 is a perspective view of a deflector detached from the heater.

To put my invention into practice, I construct the heater of sheet metal, part of which can be galvanized to provide a durable structure. The heater consists of a 35 rectangular casing 1 having its upper edges bent to provide sockets 2 for a cone shaped hood 3 adapted to connect with the register or conduit (not shown). Secured to the front and rear sides 4 and 5 of the casing 1 are cold air conduits 6 tapering from their lower ends to their upper ends. The conduits are secured to the casing 1 by bolts and nuts 7 or similar fastening means, and are adapted to convey cold air to the interior of the casing through the medium of openings 8 formed in the casing 1.

40 The interior of the casing 1 directly beneath the openings 8 is provided with brackets 9 for supporting a burner 10. The burner comprises a tapering casing 11 having its sides flanged, as at 12, to rest upon the brackets 9. In the upper end of the casing 11 is arranged a 45 piece of gauze 14 providing two layers 15 and 16 against which the ignited gas impinges, the gauze tending to retard the products of combustion until they are consumed, and for spreading the ignited gas in order that it

will contact with the cold air admitted to the heater. The lower end of the heater is located directly over a 55 gas jet 17 carried by a gas supply pipe 18 arranged in the casing 1, the supply of gas to said gas jet being controlled by a conventional form of valve 19.

Fitting in the casing 1 above the burner 10 is a deflector consisting of a front plate 20 and a rear plate 21, 60 said plates being flanged, as at 22, and bent, as at 23, to engage in the sockets 2 of the casing 1. The front and rear plates 20 and 21 extend downwardly in front of the burner 10 and provide cold air conduits 24 in front and in the rear of the burner.

Secured to the confronting faces of the plates 20 and 21, as at 25, is a V-shaped deflector 26 adapted to spread the ignited gas or products of combustion, causing the same to commingle with the cold air admitted to the casing 1 through the conduits 6 and the conduits 22^a 70 formed by the plates 20 and 21 and the flanges 22, also the cold air passing upwardly upon the sides of the burner between the deflector 26 and the plates 20 and 21.

The front side 4 of the casing 1 is provided with an 75 opening 27 alining with an opening 28 formed in the front plate 20 of the deflector structure. Hinged to the front side 4 of the casing 1 is a door 29 having a channel-shaped extension 30 upon its inner side for closing the opening 27 of the plate 20, without interrupting the passage of cold air in the conduit 22^a at the front of the heater. The door 29 is provided with a latch or lock 31 of a conventional form.

It will be apparent that I have devised a heater or furnace consisting of practically four parts, namely, the 85 casing 1, the hood 3, the burner 10 and the V-shaped deflector 26 located above the burner. These parts are easily and quickly assembled, and by providing the hinged door 29, the gas within the heater or furnace can be safely ignited.

Having fully described my invention, what I claim and desire to secure by Letters Patent is:—

1. In a heater, the combination with a gas supply pipe and jet, of a casing located over said pipe and having its upper edges flanged to provide sockets, a hood mounted in the sockets of said casing, tapering cold air conduits carried by the sides of said casing and communicating with the interior thereof, a tapering burner casing detachably mounted in said heater casing and housing said gas jet, gauze arranged in the upper end of said burner casing, a 95 V-shaped deflector detachably mounted in said casing and having front and rear plates providing air conduits, and means whereby easy access can be had to the interior of said heater.

2. A heater consisting of a casing, a tapering hood carried by the upper end of said casing, tapering cold air conduits carried by the sides of said casing and communicating with the interior thereof, a tapering burner casing located within the first mentioned casing, gauze arranged 100

in the upper end of said burner casing, a V-shaped deflector detachably mounted above said burner casing and having plates providing air conduits, and means whereby easy access can be had to the interior of said casing.

- 5 3. A heater consisting of a casing, a hood carried thereby, cold air conduits arranged at the sides of said casing and communicating with the interior thereof, a burner casing detachably mounted in the first mentioned casing, a V-shaped deflector located above said burner casing and

having plates providing cold air conduits, and means whereby easy access can be had to the interior of said casing.

In testimony whereof I affix my signature in the presence of two witnesses.

WILLIAM S. TURNER.
